COMBINED KNIFE AND HONE SHEATH

Donald H. Douglass, San Diego, Calif.

Application July 21, 1955, Serial No. 37,067

Term of patent 14 years

(Cl. D22—6)

FIG. 1

FIG. 2

Fig. 1 is a front perspective view of a combined knife and hone sheath showing my new design; and

Fig. 2 is a rear perspective view thereof. The broken line illustration of a knife and hone as shown on the drawing is for illustrative purposes only.

I claim:

The ornamental design for a combined knife and hone sheath, as shown and described.
